UNITED STATES PATENT OFFICE.

JOHN D. LANE, OF ARLINGTON, MASSACHUSETTS.

MACHINE FOR MAKING PAPER TUBES.

Application filed August 22, 1924. Serial No. 733,536.

To all whom it may concern:

Be it known that I, JOHN D. LANE, a citizen of the United States, residing at Arlington, in the county of Middlesex and

5 State of Massachusetts, have invented new and useful Improvements in Machines for Making Paper Tubes, of which the following is a specification.

This invention relates to means for forming a paper tube by winding a sheet of glue or cement-coated paper on a rotary mandrel.

The object of the invention is to provide improved means adapted to guide the leading end of the paper sheet to the mandrel 15 preparatory to the rolling operation, to continuously exert radial inward pressure on the sheet during the rolling operation, thereby compacting the tube wall on the mandrel, and to relax the said pressure after the completion of the tube.

Of the accompanying drawings forming a part of this specification,—

Figure 1 is a top plan view of a portion of a tube-making machine embodying the 20 invention.

Figure 2 is a section on line 2—2 of Figure 1 and an end view of the parts at the right.

Figures 3 and 4 are views similar to portions of Figure 2, showing different stages of the operation.

Figure 5 is a perspective view showing a portion of the gripper shown by the preceding figures, and elements of the gripper 25 tensioning and relaxing mechanism herein-after described.

Figure 6 shows in perspective portions of the mandrel and gripper, and an element of the preferred means supporting one end of the gripper.

The same reference characters indicate the same parts in all of the figures.

In the drawings, 12 designates a rotary non-expansible mandrel journaled in suitable bearings not shown, and rotated by any suitable means in the direction indicated by arrow α . The periphery of the mandrel is preferably provided with longitudinal serrations formed to engage a paper sheet 13, and cause the winding of the sheet on the mandrel, and thus convert the sheet into a tube, the sheet being coated with glue or cement.

In carrying out my invention, I provide a 35 resilient gripper 14, preferably rectangular and made of thin sheet metal, and gripper-

supporting, tensioning and relaxing mechanism organized to movably support the inner end of the gripper in close proximity to the mandrel and parallel with the axis 60 thereof, and to movably support the outer end of the gripper farther from the mandrel, the arrangement being such that the gripper includes a mandrel-embracing portion designated by 14^a in Figure 6, and a sheet-guiding portion designated by 14^b in the same figure, the guiding portion being tangential to the embracing portion. Said mechanism includes movable anchoring means engaged with the inner end of the 70 gripper, movable tensioning means engaged with the outer end of the gripper and normally exerting a yielding tension on the sheet-guiding portion of the gripper to compress or contract the mandrel-embracing 75 portion 14^a, and means for relaxing the gripper tension at predetermined periods to permit a maximum expansion of the embracing portion.

The preferred embodiments of said anchoring means, tensioning means, and tension-relaxing means, are as next described.

The anchoring means.

Mounted on a rod or cross bar 16 fixedly 85 supported above and at the rear of the mandrel, are hubs or collars 17 having arms provided with tapering slots 18, the outer ends of the slots being enlarged. Inserted loosely in the inner portions of the slots is a swinging bar or strut 19 the lower edge of which stands in close proximity to one side of the mandrel 12 and is adapted to swing toward and from the periphery of the mandrel. The inner end of the gripper 14 is fixed as 95 by electric welding, brazing or otherwise to the swinging edge portion of the strut 19. The opposite edge of the strut is held in the slots 18 by the tendency of the embracing portion of the gripper to expand.

100

The tensioning and relaxing means.

Mounted on a rod or cross bar 21 supported below and at the rear of the mandrel by fixed arms 25, is an upwardly projecting bar 22 to which the rear end of the gripper 14 is fixed as by a screw 23 secured to an ear 24 on the bar and entering an orifice in the gripper. With the bar 22 and rod 21 are engaged the opposite ends of a 110 biasing spring 26, the tendency of which is to press the bar in the direction of the ar-

row y , and thus exert, through the bar, a yielding tension on the gripper, tending to contract the mandrel-embracing portion thereof. The biasing action of the spring 26

5 is limited by stop means preferably embodied in arms 27 fixed to the bar 22 and having trundle rolls 28, and variable stop members consisting of collars 29 and cam-shaped projections 30 on said collars. The 10 collars 29 are fixed to a rotary shaft 31 journaled in fixed bearings (not shown) and rotated in the direction of the arrow z .

When the projections 30 are out of contact with the trundle rolls 28 as shown by Figure 8, the rolls bear on the collars 29, and the biasing spring 26 exerts a maximum tension on the gripper tending to contract the embracing portion thereof on the mandrel. When the projections 30 contact with the 20 trundle rolls as shown by Figures 2 and 4, the bar 22 is displaced in the direction required to relax the tension on the gripper and permit the expansion of its mandrel-embracing portion by the resilience of the 25 material of the gripper.

The leading end of the paper sheet 13 is inserted between the gripper and the mandrel when the embracing portion of the gripper is expanded as shown by Figures 2 30 and 6. The mandrel commences to wind the sheet into a tube just before the maximum pressure of the spring 26 is exerted on the gripper. As the winding progresses, the embracing portion of the gripper yields to 35 the increasing thickness of the winding, so that during the winding operation, the gripper exerts a constant radial inward pressure on the winding and presses the convolutions thereof closely together and the inner 40 convolution closely against the periphery of the mandrel. The rotation of the shaft 31 is so timed that the winding operation is completed while the projections 30 are passing from the position shown by Figure 2 45 and before they reach the position shown by Figure 4. When the arm 22 is fully displaced as shown by Figure 4, the embracing portion of the gripper expands out of contact with the completed tube.

50 In the organized machine, the mandrel is somewhat more than twice as long as the embracing portion of the gripper, and is moved endwise after the completion of each tube to remove the tube from the embracing portion and permit the winding of another tube on the portion of the mandrel within the embracing portion, the endwise movement of the mandrel being in one direction after the completion of one tube and 55 back to the original position before the next tube is wound.

The radial pressure exerted by the gripper on the paper sheet during the winding operation renders the ends of the convolutions 60 of the sheet flush with each other, so that the

ends of the tube are left even and require little or no trimming, the length of the tube being determined mainly by the width of the sheet.

I claim:

1. In a machine for forming tubes from sheet material, in combination, a rotary non-expansive mandrel; a gripper of flexible resilient sheet material; and gripper-supporting, tensioning and relaxing mechanism 70 organized to movably support the inner end of the gripper relatively near the mandrel and to movably support the outer end of the gripper farther from the mandrel, so that the gripper includes a flexible mandrel-embracing portion and a sheet-guiding portion, tangential to the embracing portion, said mechanism including movable anchoring means engaged with the embracing portion 80 of the gripper, movable tensioning means engaged with the sheet-guiding portion of the gripper and normally exerting a yielding tension on the gripper to cause the sheet-guiding portion to compress the mandrel-embracing portion, and means for relaxing 85 the gripper tension at predetermined periods to permit the expansion of said embracing portion, by the resilience of the material of the gripper.

2. In a machine for forming tubes from sheet material, in combination, a rotary mandrel; a resilient gripper; and gripper-supporting, tensioning and relaxing mechanism organized to movably support the inner end of the gripper relatively near the mandrel and to movably support the outer end of the gripper farther from the mandrel, so that the gripper includes a mandrel-embracing portion and a sheet-guiding portion, said mechanism including a swinging anchoring strut engaged with the inner end of the gripper and fixed means supporting said strut, movable tensioning means engaged with the outer end of the gripper and normally exerting a yielding tension on the gripper to compress its mandrel-embracing portion, and means for relaxing the gripper tension at predetermined periods to permit the expansion of said embracing portion.

3. In a machine for forming tubes from sheet material, in combination, a rotary mandrel; a resilient gripper; and gripper-supporting, tensioning and relaxing mechanism organized to movably support the inner end of the gripper relatively near the mandrel and to movably support the outer end of the gripper farther from the mandrel, so that the gripper includes a mandrel-embracing portion and a sheet-guiding portion, said mechanism including movable anchoring means engaged with the inner end of the gripper, an oscillatory bar engaged with the outer end of the gripper, a fixed support on which said bar is oscillatable, a biasing member adapted to exert a yielding pressure on 130

the bar to tension the gripper, and variable stop means normally maintaining the bar in its gripper-tensioning position, and adapted to displace the bar from said position 5 at predetermined periods to relax the tension of the gripper and permit the expansion of its mandrel-embracing portion.

4. In a machine for forming tubes from sheet material, in combination, a rotary 10 mandrel; a resilient gripper; and gripper-supporting, tensioning and relaxing mechanism organized to movably support the inner end of the gripper relatively near the mandrel and to movably support the outer 15 end of the gripper farther from the mandrel, so that the gripper includes a mandrel-embracing portion and a sheet-guiding por-

tion, said mechanism including movable anchoring means engaged with the inner end of the gripper, an oscillatory bar engaged 20 with the outer end of the gripper, a fixed support on which said bar is oscillatable, a biasing member adapted to exert a yielding pressure on the bar to tension the gripper, the bar being provided with lever arms, and variable stop means embodied in collars fixed 25 to a rotary shaft and adapted to alternately maintain the bar in its gripper-tensioning position and displace the bar from said position to permit the expansion of the mandrel-embracing portion of the gripper. 30

In testimony whereof I have affixed my signature.

JOHN D. LANE.
